UNITED STATES PATENT OFFICE.

MIRON D. MACK, OF KNEELAND, WISCONSIN, ASSIGNOR OF ONE-HALF TO
ELI BENSENE, OF THOMPSONVILLE, WISCONSIN.

AXLE AND AXLE-BOX.

SPECIFICATION forming part of Letters Patent No. 590,995, dated October 5, 1897.

Application filed February 15, 1897. Serial No. 623,393. (No model.)

To all whom it may concern:

Be it known that I, MIRON D. MACK, of Kneeland, in the county of Racine and State of Wisconsin, have invented a new and useful

5 Improvement in Vehicle-Axes and Axle-Boxes, of which the following is a description, reference being had to the accompanying drawings, which are a part of this specification.

10 My invention has relation to improvements in vehicle-axes and axle-boxes.

The object of the device is to effectually provide on the one hand for excluding all dirt or sediment and on the other to prevent the 15 escape of the oil or lubricant.

With the above primary object in view the invention consists of the devices and parts or their equivalents, as hereinafter more fully set forth.

20 In the accompanying drawings, Figure 1 is a detail of one end of an axle of my improved construction, showing the packing, before being compressed, in proper position thereon. Fig. 2 is a similar view of the axle, showing 25 the box thereon and the packings compressed into the annular grooves, said box being in longitudinal section. Fig. 3 is a cross-section on the line 3-3 of Fig. 2. Fig. 4 is a detail view of one of the packing-rings; and Fig. 30 5 is a view of a modified form of one end of the axle and axle-box with the nut on the end thereof, said box and nut being in section.

Referring to the drawings, the numeral 6 indicates the main portion of the axle, terminating at its extremity in the spindle 7. At the point where the spindle joins the main portion of the axle an annular shoulder 8 is formed, and immediately in advance of said shoulder the spindle is provided with an annular groove 9. At a short distance outwardly from the annular groove the spindle is advantageously formed with another annular shoulder 10, the spindle from this latter shoulder outwardly being of a reduced diameter, leaving the portion 11 between the shoulders 8 and 10 of a somewhat greater diameter than the remaining portion of the spindle, but of less diameter than the main portion of the axle. Near its outer end the spindle is provided with a third shoulder 12, and immediately in advance of this shoulder with an an-

nular groove 13. From this annular groove the spindle continues outwardly in a reduced extremity, the inner portion thereof being plain, as indicated at 14, and the remaining 55 portion threaded.

The numeral 15 indicates the axle-box. This box is adapted to receive therein the axle-spindle and to closely embrace the spindle, including the portion 11 thereof. This 60 box is provided with an interior annular shoulder 16, which is opposed to the shoulder 8 of the axle and is also formed with an annular groove 17, which registers with the annular groove 9. The extremity of the bore of this 65 box is somewhat enlarged to fit closely around the axle proper. In cases where the spindle is provided with the shoulder 10 the box is correspondingly shouldered, as indicated at 18, and between these two shoulders is advisably interposed a packing 19. The remaining portion of the bore of the box is of a reduced diameter to fit the correspondingly-reduced portion of the spindle. Near its outer end the box is provided interiorly with a 70 shoulder 20 and just in front of this shoulder with an annular groove 21, registering with the annular groove 13 of the spindle. The extreme outer end of the bore of the box is reduced in diameter to fit snugly around the 75 plain or unthreaded portion 14 of the reduced extremity of the spindle. The box is held in position on the axle by means of a nut 22, engaging the threaded extremity of said axle. The outer surface of the box is also provided 80 with the usual ribs 23, which are adapted to engage grooves in the hub of the wheel in the ordinary and well-known manner in order to lock said wheel to the axle-box. The portion 11 of the spindle forms a seat for a 85 packing-ring 24, said ring being preferably of the shape shown in Fig. 4 and being composed of any suitable material adapted for the purpose. A similar but smaller packing-ring 25 surrounds the inner portion of the 90 outer reduced extremity of the spindle adjacent to the shoulder 12. Fig. 1 of the drawings shows these rings in proper position on the spindle. Now when the spindle is forced into the axle-box the shoulders 8 and 12 of 95 the spindle and the shoulders 16 and 20 of the box tend to force and compress the annular

packing-rings into the annular registering grooves of the axle and box. This is shown clearly in Fig. 2, wherein the flat packing-rings are compressed into these annular grooves, so as to completely fill the spaces thereof. After the box and axle are thus adjusted together the nut 22 is then screwed onto the extremity of the spindle, and the several parts are thus properly adjusted together. When thus connected, it is obvious that it would be very difficult for any dirt or sediment to pass into the box between said box and spindle, inasmuch as the packing-rings 24 and 25 completely fill up the spaces of the registering annular grooves, and thus effectually close the joints. On the other hand it is equally difficult for the oil or other lubricant to escape from within the journal-box. The annular shoulder 10 of the spindle, it will be observed, will contact with the shoulder 18 of the box, and thus limit the extent to which the axle can be forced into the box. These coacting shoulders are therefore advisably employed. However, if preferred, they could be omitted without departing from the spirit and scope of my invention, and in that event the spindle would continue outwardly of the same diameter as the portion 11 thereof as far as the end shoulder 12, and the bore of the axle-box would be of course of a corresponding diameter.

In Fig. 5 of the drawings I have shown a slightly-modified form of construction, in which instead of employing the end shoulder 12 and the annular groove 13 near the outer end of the spindle I provide the exterior surface of the box 15 with an annular shoulder 26 and with an annular groove 27, adjacent to said shoulder. A modified form of nut for the end of the spindle is employed in this modification. This nut is indicated by the numeral 22' and is provided with an annular shoulder 28, which fits against the end of the axle-box, and is also formed at its inner end with an extension 29 of greater diameter than the threaded portion of the nut. This extension is not threaded interiorly, but is formed within its bore with an annular shoulder 30, which is opposed to the annular shoulder 26 of the axle-box. It is also formed with an annular groove 31, which registers with the annular groove 27. Within these registering annular grooves the packing-ring 25 is adapted to be forced, so as to fill up the space and tightly close the joint. I also show in Fig. 5 an improved means of feeding the oil or lubricant to the parts. It consists of tapping a recess 32 from the outer end of the spindle inwardly for a desired distance and then running a branch recess 33 downwardly. The oil can then be readily fed through the recess 32 and pass down the branch recess 33 to the parts to be lubricated. After the oil is fed into the recess 32 the closed nut is adjusted over the end of the spindle to prevent the oil from escaping.

What I claim as my invention is—

1. In a vehicle-axle and box, the combination, of an axle provided with a groove therearound, one of the side walls of said groove 70 extending out beyond the grooved surface to form a projecting shoulder, an axle-box provided with an internal groove therearound, one of the side walls of said groove extending inwardly beyond the grooved surface to form 75 a projecting shoulder, said shoulder, when the parts are fitted together, being opposed to the shoulder of the axle, and the two grooves of the box and axle registering, and a packing adapted to be compressed into the registering grooves by the action of the opposed shoulders. 80

2. In a vehicle-axle and box, the combination of an axle provided near its outer end with a shoulder therearound and with an encircling groove 85 adjacent to the side of the shoulder, and also provided at a point farther inward with another shoulder, and with a groove adjacent to the side of said shoulder, an axle-box provided with sets of shoulders 90 and with sets of grooves, the shoulders when the parts are fitted together being opposed to the shoulders of the axle, and the grooves registering with the grooves of said axle, and packings adapted to be compressed into the 95 registering grooves by the action of the opposed shoulders, when the parts are fitted together.

3. In a vehicle-axle and box, the combination, of an axle provided with a shoulder 100 therearound and with an encircling groove adjacent to the side of the shoulder, said axle also provided with another shoulder at a point nearer the end of the axle, an axle-box provided with a shoulder and with a groove adjacent to the side of the shoulder, and also provided with another shoulder, the shoulders of the box, when the parts are fitted together, being opposed to the shoulders of the axle, and the grooves registering with the grooves 105 of said axle, and packing adapted to be compressed into registering grooves by one set of the opposed shoulders.

4. In a vehicle-axle and box, the combination, with an axle, an axle-box, and an end 115 nut, one of said parts being provided with a shoulder therearound, and with a groove adjacent to the side of the shoulder, and another of said parts with a shoulder and with a groove adjacent to the side thereof, the 120 shoulders, when the parts are fitted together, being opposed, and the grooves registering, of a packing adapted, when the parts are fitted together to be compressed into the registering grooves by the opposed shoulders. 125

In testimony whereof I affix my signature in presence of two witnesses.

MIRON D. MACK.
